UNITED STATES PATENT OFFICE.

WALTER WILLIAM PHILLIPS, OF LONDON, ENGLAND, ASSIGNOR TO PHILLIPS' PATENTS LIMITED, OF LONDON, ENGLAND.

DESIGN FOR A RUBBER HEEL-PAD FOR FOOTWEAR.

48,042.

Specification for Design.

Patented Oct. 26, 1915.

Application filed April 13, 1915. Serial No. 21,141. Term of patent 14 years.

To all whom it may concern:

Be it known that I, WALTER WILLIAM PHILLIPS, a subject of the King of Great Britain and Ireland, residing at London, England, have invented a new, original, and ornamental Design for Rubber Heel-Pads for Footwear, of which the following is a specification, reference being had to the accompanying drawings, forming part thereof.

Figure 1 is a section on the line A B of

Fig. 2 and Fig. 2 is a plan of a rubber heel pad for footwear.

I claim

The ornamental design for a rubber heel pad for footwear, as shown.

WALTER WILLIAM PHILLIPS.
